UNITED STATES PATENT OFFICE.

LEWIS M. PYLE, OF BRYN MAWR, PENNSYLVANIA, ASSIGNOR TO NILES-BEMENT-POND COMPANY, OF NEW YORK, N. Y., A CORPORATION OF NEW JERSEY.

PLANER.

Application filed January 13, 1921. Serial No. 436,968.

To all whom it may concern:

Be it known that I, LEWIS M. PYLE, a citizen of the United States, residing at Bryn Mawr, in the county of Montgomery and State of Pennsylvania, have invented certain new and useful Improvements in Planers, of which the following is a specification.

This invention relates to metal working machines of the reciprocating tool or work type such as planers, shapers and the like and the primary object of the invention is to provide improved operating mechanism particularly applicable to such machines.

15 It is an object of the invention to provide in combination with a tool or work support, a reciprocating block adjustably secured to the tool or work support, improved means for clamping the block in its adjusted position and readily accessible means for adjusting the block and operating the clamping means.

25 It is an object of the invention to provide in combination with the reciprocating means, a two-part oscillating link or rocker arm, one part being telescopically mounted for free sliding movement within the other part whereby to compensate for the difference in distance between the two respective outer ends of the said parts at the different positions of the reciprocating support.

35 Another object of the invention comprises an automatic feed compensating mechanism operated preferably from the main source of power and adapted to operate the feeding mechanism at a relatively rapid speed during the idle stroke of the tool or work support to feed one of such supports transversely of the cutting stroke.

40 With the above objects particularly in view, the invention will now be described by reference to the drawings wherein:

45 Figure 1 is a plan view, partly broken away and partly in section on the line 1—1' of Fig. 2, showing a planer comprising the present invention.

Fig. 2 is a side elevation thereof partly broken away.

50 Fig. 3 is an end elevation thereof partly in section on the line 3—3' of Fig. 1.

Fig. 4 is a transverse sectional view through the planer bed on the line 4—4' of Fig. 2.

55 Fig. 5 is an enlarged detail view of the

reciprocating block in connection with its adjusting and clamping means.

Fig. 6 is a side view thereof.

Fig. 7 is an enlarged face view of the feed compensating mechanism.

Fig. 8 is a sectional view thereof on the line 8—8 of Fig. 7.

Fig. 9 is an enlarged sectional view of the stroke adjusting and clamping means on the line 9—9 of Fig. 3.

Fig. 10 is a face view of the stroke adjusting means.

The improved mechanism comprising the present invention is particularly applicable to planers, shapers, and metal working machines wherein is a tool support, a work support, means for reciprocating one support and means for giving the tool and work a relative feeding movement transversely of the line of reciprocation. The invention, as illustrated in the drawings, is shown in connection with a planer of the usual type having a reciprocating table above which is a cross rail supporting a tool head thereon. It will be understood, however, that the improvements comprising the invention are not limited particularly to a planer but are applicable to other machines of a like character within the scope of the claims appended hereto.

Referring more specifically to the drawings, 1 designates the base or bed of a planer on which is slidably mounted a work table 2. This table is adapted to be reciprocated by means of an oscillating link 3 driven by a motor 4 through the improved mechanism to be hereinafter described. A cross rail 5 is supported on uprights 6 mounted on the bed and a tool support 7 is mounted on the rail for feeding movement transversely of the work table. Screws 8 serve to elevate the cross rail on the uprights. A screw 9 and screw shaft 9' serve respectively, through other improved mechanism to be described, to feed the tool support horizontally along the rail and vertically thereof.

The drive from the motor 4 to the link 3 and table 2 is as follows. A pinion 10 on the motor shaft meshes with a gear 11 on a shaft 12 also carrying a pinion 13 meshing with a gear 14 on a shaft 15. A pinion 16 secured to the gear 14 meshes with a gear 17 keyed to a rotary driving drum 18. The inner face of the drum 18 (Figs. 1, 3, 9) is

and 10) is provided with a radial guideway 19 in which is mounted a slide 20 adjustable by means of a screw 21. A pin 22 carrying a block or driver 23 freely slidable within 5 a longitudinal guideway 24 in the link 3 is provided on the slide at one end thereof. The link is pivoted at its lower end to the bed at 25 and at its upper end at 26^a to a block 26 adjustably secured to the table. 10 The screw 21 is journaled at one end in a bearing 27 and a bevel gear 28 thereon adjacent the bearing meshes with a bevel gear 29 on a tubular shaft 30 mounted in bearings 31 within the drum. At its outer end 15 (Fig. 9) this shaft has non-rotatably mounted thereon a second sleeve 32 on which is keyed an adjusting hand wheel 33. Rotation of the hand wheel is adapted to rotate the screw to adjust the driver toward and 20 from the center of the drum thereby varying the throw of the link 3 and the reciprocation of the table.

An indexing dial 34 is provided for indicating the amount of rotative movement given 25 to the hand wheel 33 and the position of the block 23. In adjusting the block 23 from zero to maximum, the shaft 30 must be given several rotations. In order to properly record these rotations, the indexing dial 30 34 is adapted to be rotated from the shaft 30 at a greatly reduced speed through the following mechanism: An internal gear 35 is secured to the drum 18 and an external gear 36 is freely mounted eccentrically of the shaft 30 on an eccentric portion 32^a of the sleeve 32 and connected to the dial 34 by means of a screw 37. The internal gear 35 has a greater number of teeth than the external gear 36. The gears 35 and 36 are always in mesh and as the sleeve 32 is rotated, the meshing position of these gears travels around the shaft 30. It will be seen that for 40 each such rotation, the dial 34 is rotated relative to the gear 35 the distance of the difference of the number of teeth on gears 35 and 36. The dial may be marked to clearly 45 indicate the effect of any adjustment of the hand wheel on the table stroke. This mechanism forms a part of the subject matter of a copending application hereinafter specified.

The slide 20 is bifurcated at one end, providing two legs 20^a and 20^b fitting in grooves 19^a and 19^b on opposite sides of the guideway 19 (Figs. 9 and 10). A wedge block 38 having inclined sides 38^a and 38^b engaging complementary surfaces within the bifurcated portion of the slide is adapted to be forced inwardly of the slide to wedge the legs 20^a and 20^b thereof into tight clamping engagement with the drum. As illustrated, the block 38 entirely surrounds the screw 21, although, as will be understood, such construction is not essential to a realization of the invention. The means for forcing the block 50 into clamping engagement comprises a shaft

39 preferably integral with the block and extending through the tubular shaft 30. A nut 40 is threaded to the end of shaft 39 and has bearing against the sleeve 32 which at its inner end bears directly against the drum. 70 After adjustment of the slide 20 by means of the hand wheel 33, the former may be tightly clamped in adjusted position by tightening the nut 40. It should be noted that the means for operating the parts just described is remote from the parts themselves and is readily accessible, it being only necessary for the operator to swing open the pivoted cover member 41. I do not claim this stroke adjusting mechanism just 75 described as a part of my invention, the same being the invention of Herbert S. Fullerton and comprising the subject matter of a co-pending application, Serial No. 436,964, filed 80 January 13, 1921.

As the table is reciprocated through the oscillatory movement of the link 3, it will be noted that the distance between the pivots 25 and 26^a is different for different positions of the table and such distance is constantly changing as the table is being reciprocated. To compensate for this difference, I preferably make the link in two relative sliding parts, one telescopically mounted for free sliding movement within the other. As illustrated in Figs. 1 and 2 the outer lower part 3^a of the link is pivoted at 25 and the upper inner part 3^b is pivoted at 26^a. Adjusting blocks 42 and 43 are provided in the guideways in the part 3^a of the link for taking up lost motion and looseness caused by wear or otherwise.

It is often desirable and necessary to adjust the operating position of the table on the bed and for this purpose, I provide the following improved mechanism. The block 26 is mounted in a dove-tailed recess 44 extending lengthwise of the table at the under side thereof (Figs. 1, 2, 3, 5 and 6). A screw 45 journaled at one end 46 in the table end 110 has threaded engagement with the block whereby the position of the block within the table recess may be adjusted. The block has a portion thereof cut away to form a recess 115 within which is mounted a wedge block 47 having a straight side 47^a engaging one wall of the table recess and an inclined or tapered side 47^b engaging a complementary surface on the block 26. A sleeve 48 has threaded engagement with the wedge block and an elongated squared portion 49 of a shaft 50 fits a like longitudinal bore in the threaded sleeve. The shaft 50 extends parallel of the screw 45, is journaled adjacent thereto in the table end at 51 and is freely slidable within the sleeve 48. It will be seen that by rotating the shaft 50 the wedge block 47 may be moved in one direction or the other to clamp the block 26 tightly within the recess 44 or to unclamp the same.

In machines of the general type defined herein, the reciprocating tool or work support is given a slow cutting movement in one direction and a relatively rapid movement in the opposite direction on the idle or non-cutting stroke. In the machine illustrated in the drawings, the drum 18 is rotated from the motor at a uniform or constant speed in the direction indicated by the arrow in Fig. 2. Since the driver 23 is relatively near the pivot 25 during the idle stroke and relatively far from the pivot 25 during the working stroke, the idle and working strokes will be relatively fast and slow respectively. The feeding of the tool must be accomplished during the idle stroke and in order to compensate for the much less time consumed in the idle stroke, means is provided for giving the feed mechanism a relatively high speed during such time.

Referring to Figs. 1, 2 and 4, it will be seen that a pinion 52 on the shaft 15 meshes with a gear 53 mounted to rotate freely on a trunnion 54 secured to the machine frame by screws 54 (Figs. 7 and 8). A shaft 55 (Fig. 4) extends transversely of the bed and an extension 56 thereof projects eccentrically through the trunnion 54 and carries a disk 57 at its outer end adjacent the gear 53, the gear preferably being recessed to receive the disk, as illustrated. The disk is adapted to be driven from the gear through a pin and slot connection comprising a radial slot 58 in the disk engaged by a driving block 59 on a pin 60 set in the gear. The gear 53 is given a uniform rotation from the motor, however, the driving block 59 being nearer the axis of the shaft 55 during a portion of the rotation of gear 53, the disk 57 and shafts 55 and 56 are given a relatively rapid rotative movement at this time. As clearly illustrated in Fig. 7 the uniform rotation of gear 53 causes a variable rotation of the shaft 55 which reaches its maximum speed when the driving block 59 is nearest the axis of shafts 55 and 56. In Fig. 7 the position of the block is such as to impart the minimum speed to the disk 57 and shafts 55 and 56. The shaft 55 is provided at its outer end with a crank arm 61 adjustable radially of the shaft 55 and operably connected through a rod 62 to a rack 63 meshing with a gear 64 on a vertical tool feeding shaft 65. The shaft 65 is operatively connected to the tool feeding screw 9 and screw shaft 9^a through the usual two-way ratchet connection which comprises no part of the present invention and is therefore not described herein.

The general operation of the machine is as follows: The table may be adjusted to the desired position on the bed by means of the screw 45 and clamped in adjusted position by the shaft 50 operating the wedge block 47. The stroke of the table may be

adjusted from zero to maximum by turning the hand wheel 33 to move the driver 23 toward or from the center of the drum and may be clamped in adjusted position by means of the nut 40. As the drum is rotated, the block 23 travels in the guideway 24 and the direction of the rotation being that illustrated by the arrow in Fig. 2, the cutting stroke is relatively slow and the idle or non-cutting stroke relatively fast. The tool feeding mechanism heretofore described is so connected to the table driving mechanism that the block 59 is in its downward position (Fig. 7) nearest the axis of shaft 55 during the idle stroke of the table; therefore, the feed shafts 55 and 65 are given the maximum relatively high rotative movement at this time to feed the tool. The extent of tool feed may be varied by adjusting the crank arm 61 radially of the shaft 55.

What I claim is:

1. In combination with a metal working machine comprising a work support and a tool support, one of such supports being reciprocally mounted, a block secured to the reciprocable support, means operably secured to the block for reciprocating the support, means for adjusting the block along the support in the direction of its reciprocation, a sliding wedge for clamping the block in position, and means for operating the wedge.

2. In combination with a metal working machine comprising a work support and a tool support, one of such supports being reciprocably mounted, a block secured to the reciprocable support, means operably secured to the block for reciprocating the support, means for adjusting the block along the support in the direction of its reciprocation, a wedge extending longitudinally of the block for clamping the block in position, and a screw for sliding the wedge in a direction substantially parallel of the adjustable movement of the block for clamping the block in position.

3. In a planer, the combination of a reciprocating table having a longitudinal recess therein, a block mounted in the recess and adjustably secured to the table, means operably secured to the block for reciprocating the table, block clamping means in the recess adjacent the block, and means exterior of the table at one end thereof for operating such members to adjust the block longitudinally of the table in the recess and for clamping the same in adjusted position.

4. In a planer, the combination of a reciprocating table having a longitudinal recess therein, a block mounted in the recess and adjustably secured to the table, means operably secured to the block for reciprocating the table, means for adjusting the block along the recess in the direction of the table reciprocation, a wedge extending longitudinally of and adjacent the block

in the table recess, and a screw for operating the wedge to secure the block in position.

5. In a planer, the combination of a reciprocating table having a longitudinal recess therein, a block mounted in the recess and adjustably secured to the table, means operably secured to the block for reciprocating the table, a screw extending longitudinally of the table and engaging the block 10 for adjusting the same in the recess, a sliding wedge extending longitudinally of and adjacent the block in the recess, a screw for operating the wedge to secure the block in position, and means exterior of the table 15 for operating the screws.

6. In combination with a metal working machine comprising a bed, a work support and a tool support, and means for reciprocating one support comprising a relatively 20 sliding two-part member, one part being pivoted to the bed at its lower end and provided with a guideway portion extending upwardly above the pivot, the other part being pivotally secured to the reciprocating 25 support at its upper end and provided with a guideway portion extending downwardly from the pivot, and the said two guideway portions being telescopically mounted one within the other.

30 7. In combination with a metal working machine comprising a bed, a work support and a tool support, means for reciprocating one support comprising a relatively sliding two-part member, one part being pivoted 35 to the bed at its lower end and provided with a guideway portion extending upwardly above the pivot, the other part being pivotally secured to the reciprocating support at its upper end and provided with 40 a guideway portion extending downwardly from the pivot, the last named guideway portion being telescopically mounted for free sliding longitudinal movement within the first named guideway portion, and 45 means engaging the first named part for oscillating the same.

8. In a planer, the combination of a bed, a reciprocating table, and means for reciprocating the table comprising an oscillating member pivoted at its lower end to the bed and provided with a guideway portion extending upwardly from the pivot, a second member pivoted at its upper end to the table and telescopically mounted for free sliding longitudinal movement within the said guideway portion of the first named member, and power means engaging the first member to oscillate the same.

60 9. In a metal working machine, the combination of a bed, a work support, a tool support, means for reciprocating one of the supports slowly in the cutting direction and rapidly in the idle direction, and feeding mechanism comprising a uniformly rotated member, a second member adapted to be ro-

tated thereby at a relatively rapid rate during the idle stroke of the reciprocating support and means connecting the second member to one support for feeding the same transversely of the said reciprocation during 70 the idle stroke.

10. In a metal working machine, the combination of a bed, a work support, a tool support, means for reciprocating one of the supports slowly in the cutting direction and rapidly in the idle direction, and feeding mechanism comprising a uniformly rotated member, a second member mounted eccentrically of the first member and adapted to be rotated thereby at a relatively rapid rate 75 during the idle stroke of the reciprocating support and means connecting the second member to the tool support for feeding the same transversely of the said reciprocation 80 during the idle stroke.

85 11. In a planer, the combination of a bed, a reciprocating table, means for reciprocating the table slowly in the cutting direction and rapidly in the idle direction, a tool support, tool feeding mechanism comprising a screw operatively connected to the tool support, a uniformly rotated member, a second member adapted to be rotated thereby at a relatively rapid rate 90 during the idle stroke of the table and means connecting the second member to the screw for feeding the tool support transversely of the table reciprocation during the idle stroke of the table.

95 12. In a planer, the combination of a bed, a reciprocating table, means for reciprocating the table slowly in the cutting direction and rapidly in the idle direction, a tool support, tool feeding mechanism comprising a screw operatively connected to the tool support, a member rotated synchronously 100 from the table driving means, a second member mounted eccentrically of the first member, a pin and slot connection between the two members whereby the second member is rotated at a relatively rapid rate during the idle stroke of the table, and means connecting the second member to the screw for feeding the tool support transversely of the table reciprocation 105 during the idle stroke of the table.

110 13. In a planer, the combination of a bed, a reciprocating table, means for reciprocating the table slowly in the cutting direction and rapidly in the idle direction, a tool support, tool feeding mechanism comprising a screw operatively connected to the tool support, a member rotated synchronously from the table driving means, a second member mounted eccentrically of the first member 115 and adapted to be rotated thereby at a relatively rapid rate during the idle stroke of the table and means comprising a crank arm operatively connecting the second member to the screw for feeding the tool support transversely of the table reciprocation in either 120 125 130

direction during the idle stroke of the table.

14. In a planer, the combination of a bed, a reciprocating table, means for reciprocating the table slowly in the cutting direction and rapidly in the idle direction, a tool support, tool feeding mechanism comprising a screw operatively connected to the tool support, a gear rotated synchronously from the table driving means, a disk mounted on a 10 shaft eccentric of the gear axis, a projec-

tion on the gear engaging a radial slot in the disk for driving the same at a relatively rapid rate during the idle stroke of the table and means connecting the second member to the screw for feeding the tool support transversely of the table reciprocation during the idle stroke of the table.

In testimony whereof, I hereto affix my signature.

LEWIS M. PYLE.
